DEICING APPARATUS

Edgar L. Vail, New York, N. Y., assignor to Jaeger
Watch Company, Inc., New York, N. Y., a cor-
poration of New York

Application March 16, 1939, Serial No. 262,132

9 Claims. (Cl. 244—134)

This invention relates to deicing equipment, and more particularly to means whereby equipment of this kind is associated with a rotating mechanism to prevent ice from forming on the surfaces of said mechanism.

A well-known and undesirable phenomenon in aircraft operation is the formation of ice on the surfaces of the craft, and this condition is particularly objectionable when it occurs upon moving parts, such as a propeller constituting a part of an indicating instrument. Aircraft instruments of this type usually comprise an indicating unit in the cockpit operatively connected to a propeller unit mounted on the wing of the aircraft. If ice is formed on the propeller unit, the speed of the propeller is varied independently of the speed of the craft and the readings of the indicating unit are thus rendered inaccurate and useless. Furthermore, the formation of ice on a rotating body creates unbalanced centrifugal and inertia forces which set up vibrations creating excessive stresses which may render the entire unit inoperative.

It is accordingly an object of the present invention to provide novel deicing means in combination with a rotating member such as the propeller of an indicating device.

Another object is to provide, in combination with the propeller unit of an air speed indicator, a novel fluid ejecting mechanism which does not increase the wind resistance of said unit.

A further object is to provide a novel compact impeller unit adapted for effective and accurate operation at high altitudes and/or low temperatures.

Still another object is to provide a novel deicing mechanism which is positive in action and capable of producing a desired spray of anti-freeze fluid over a selected surface or surfaces.

The above and other objects and novel features of this invention will more fully appear from the following detailed description when the same is read in connection with the accompanying drawing. It is to be expressly understood, however, that the drawing is for purposes of illustration only and is not intended as a definition of the limits of the invention, reference being had for this purpose to the appended claims.

In the drawing, wherein like reference characters refer to like parts throughout the several views,

Fig. 1 is a view, partly in elevation and partly in section, showing one form of the present invention in combination with an impeller unit;

Fig. 2 is a sectional view taken substantially along line 2—2 of Fig. 1;

Fig. 3 is a sectional view taken substantially along line 3—3 of Fig. 1;

5 Fig. 4 is a view, partly in elevation and partly in section, with parts broken away, showing, somewhat diagrammatically, the above embodiment operatively associated with a source of anti-freeze fluid; and,

10 Fig. 5 is an enlarged fragmentary section of a portion of the mechanism shown in Fig. 1.

The single embodiment of the invention illustrated comprises a cylindrical casing 10 which is secured by suitable means to a plane wing (not shown) and has a bearing member or housing 11 concentrically mounted therein and rigidly secured thereto by screws 12. Two bearings 13, each preferably sealed at one end and axially spaced by a separating sleeve 14, are carried by 15 said member and journal a hollow shaft 15 extending axially in both directions beyond member 11 and having a central portion 16 of increased diameter, the edges of said portion engaging the plane faces of said bearings and fixing 20 said shaft against axial movement. A hub 17 is preferably keyed to the portion of shaft 15 extending, as viewed in the drawing, beyond the left end of member 11, and a plurality of 25 propeller blades 18, two being shown in the present embodiment, are securely fixed to said hub, preferably by a band 19, being spaced at equal distances around the circumference of said hub. The left end of said shaft is externally threaded 30 and a nut 20 is screwed thereon to axially secure 35 said hub.

Hub 17 constitutes the leading end of the impeller unit and is provided with a cap 21 which is preferably secured to said hub by a force fit, and said hub and cap are shaped in accordance 40 with well-known principles of streamlining in order to reduce the air resistance of said unit. A space or chamber 22 is thus created between said cap and said hub.

When the airplane upon which the impeller 45 unit is mounted is in flight, propeller 17, 18 is rotated at an angular speed proportional to the speed of the plane and propels shaft 15 at the same speed. In order to convert this rotation into a speed reading on an instrument remote from said impeller, means are provided for interrupting an electrical current at a frequency proportional to the shaft velocity. Said means 50 preferably comprise a cylindrical member 23 of insulating material eccentrically mounted on a sleeve 24 secured to shaft 15 and adapted to en-

gage a pair of resilient contacts 25 (Fig. 2), each of the latter being fixed at one end to a terminal 26 and having the other end urged into resilient engagement with a terminal 27. Each of said terminals is secured to or formed with an annular insulation member 28 and the latter is in turn fixed to member 11. Each of said terminals also is electrically connected by insulated conductors 29 (Fig. 1) to one of prongs 30 carried by an insulated socket 31, the latter being fixed to and constituting the right end of the impeller unit. Eccentric 23, when rotating, moves contacts 25 radially and once during each revolution breaks the circuit between said contacts and terminals 27, thereby creating an interrupted circuit having a frequency corresponding to the angular speed of shaft 15. Suitable connecting means (not shown) may be provided to plug into socket 31 and to transmit current through the two circuits comprised by contacts 25 and terminals 26 and 27 from a source of electrical energy and to thereafter convey the interrupted current to a suitable indicating instrument.

It is fairly obvious that any increase in weight of the moving parts of the impeller unit, as by the formation of ice thereon, particularly when the weight is located to create unbalanced inertia and centrifugal forces, will materially change the angular speed of propeller 17, 18 for any given plane speed. This will render the impeller unit and the apparatus connected thereto ineffective and useless as a measuring instrument. Accordingly, it is very important that formation of ice on the impeller parts, particularly on propeller 17, 18 and cap 21, be prevented, and novel deicing means are provided and novelly combined with the impeller unit to keep the latter coated during flight with a suitable anti-freeze fluid, such as a mixture of glycerine and alcohol. As illustrated, said means comprise a reservoir or supply tank 32 (Fig. 4) containing said anti-freeze mixture under a pressure preferably of about four or five pounds per square inch above atmospheric, the pressure being maintained through a conduit 33 connecting said reservoir with a suitable high pressure source (not shown) associated with the engine, as, for example, a pump. Reservoir 32 is preferably mounted in a wing, and suitable control means in the form of a valve 34 are provided in conduit 33 within reach of the airplane operator whereby said reservoir may be disconnected from the source of pressure.

The anti-freeze fluid flows from reservoir 32 through a conduit 35 which is preferably flexible and which is connected by a coupling 36 to a tube 37 of a suitable flexible metal such as copper. Coupling 36 comprises a needle or conical valve 38 having a spring 39 normally holding said valve in closed position and prevention any back flow of fluid from tube 37 to tube 35 and further preventing any flow from tube 35 to tube 37 unless the fluid in reservoir 28 is under pressure. Accordingly, since the pressure in said reservoir is only built up during operation of the airplane engine, there is no flow of fluid when the engine is inoperative. Tube 37 fits snugly into an opening or slot 40 provided through socket 31 and extends through said opening into casing 10. A fairly stiff capillary tube 41, preferably of stainless steel, is connected to the end of tube 37 by suitable means such as a coupling 42, the latter being joined to said tubes by solder to form fluid-tight connections therewith. A narrow bracket or support 43 extends diametrically across cas-

ing 10, being formed integrally with a pair of axially extending arms 44 which are, in turn, integral with a ring 45 encircling and secured to bearing member 11, said ring being interposed between said member and said casing.

An opening 46 partly threaded, the unthreaded portion thereof being conical in shape, is provided in support 43, being centrally located relative to casing 10, and tube 41 is adapted to extend radially to the center of said casing and then pass through said opening. In order to fix said tube in central position, a clamp nut or screw 47 encircles said tube and is threaded in opening 46, being provided with a somewhat resilient conical tip which engages the conical wall of said opening and as said screw is threaded into said opening the tip is compressed radially and tightly grips tube 41. From said clamp nut said tube is directed through hollow shaft 15 and extends beyond the end of said shaft into chamber 22 between cap 21 and hub 17.

The anti-freeze fluid which flows from reservoir 32 into chamber 22 is adapted to fill the latter and is prevented from flowing back through the space between tube 41 and hollow shaft 15 by packing means associated with said tube and said shaft. Said means comprise a plurality of washers 48 (Fig. 5) of some suitable resilient material such as rubber or leather, the edges and walls of said washers being compressed in fluid tight engagement with the periphery of tube 41 by a nut 49 which is provided with a shoulder 50. Nut 49 is screwed on the threaded end of shaft 15 and said washers are compressed and held between shoulder 50 and the end of shaft 15 and rotate with said shaft when the latter is driven by propeller 17, 18. In addition to minimizing leakage from chamber 22, washers 48 support the end of tube 41 maintaining said tube rigid and concentric with shaft 15, and therefore keeping the same from rubbing against the wall of said shaft.

In order to provide means for ejecting the anti-freeze fluid from chamber 22, a small opening 51 (Fig. 1) about .01 inch in diameter is provided at the foremost tip of cap 21 and a plurality of openings 52 are located about the periphery of said cap in proximity to the junction thereof with hub 17. Four of openings 52, approximately .005 inch in diameter, equally spaced about the circumference of said cap, have been found to be satisfactory for a proper ejection of the fluid and for producing a desired spray thereof. The fluid which flows from opening 51 spreads rearward over the surface of cap 21, completely coating the latter, whereas the fluid from openings 52 is sprayed radially into the path of propeller 17, 18 and coats at least the hub of the latter, being thereafter spread by the centrifugal forces acting thereon to the tips of the propeller blades.

In operation, the impeller unit is actuated by the wind flowing past propeller 17, 18 at a relatively high speed, causing the latter to rotate and drive shaft 15 at a rate determined by the speed of the airplane upon which said impeller unit is mounted. Shaft 15 causes eccentric 23 to break each of two electric circuits comprised by contacts 25 and terminals 26 and 27, once for every revolution thereof, and these interrupted electrical currents are conducted from socket 31 to a remote indicating instrument to preferably provide a visual record of the speed or distance of travel of the airplane.

The deicing equipment is set into operation with the airplane motor, the latter building up

a pressure in reservoir 32 which overcomes the resistance of spring 39 to open valve 38 and permits the flow of anti-freeze fluid from said reservoir through conduits 35, 37 and 41 to chamber 22. The fluid is thereafter ejected through openings 51 and 52 and is caused to coat substantially the entire impeller unit surface, including stationary and moving parts. The flow of anti-freeze fluid is preferably continued during the entire flight, although the operator of the airplane may shut off reservoir 32 from the pressure source by means of valve 34, thus permitting spring 39 to close valve 38 and thereby prevent a further fluid flow.

There is thus provided a novel combination of deicing equipment with a streamlined unit whereby the latter is effectively coated with a film of anti-freeze fluid during flight, said equipment having no externally projecting members which tend to increase the air resistance of said unit. There is also provided a novel means for mounting deicing equipment in a rotary unit whereby the external moving parts of said unit are sufficiently sprayed with anti-freeze fluid to prevent the formation of ice thereon. An impeller unit equipped with the above invention becomes operable to actuate an indicating instrument accurately under any atmospheric conditions and particularly under conditions which would, except for the present invention, cause the formation of ice on the moving parts of the impeller. The deicing equipment is neither a complex nor a delicate apparatus and is accordingly easy to install and certain in operation, ready means for controlling said equipment being within easy reach of the airplane operator.

Although only a single embodiment of the present invention has been illustrated and described, it is to be expressly understood that the same is not limited thereto. For example, it will now be apparent to those skilled in the art that the deicing equipment may be utilized with equal facility upon other rotating devices such as impeller units of the type which transmit energy to the indicating instruments mechanically and not electrically. Furthermore, the connecting conduits from reservoir 32 to chamber 22 may be replaced by a single tube. Various other changes may be made without departing from the spirit and scope of the invention. For a definition of the invention, reference will be had primarily to the appended claims.

What is claimed is:

1. In combination with a rotating unit to be deiced, a reservoir carried in front of said unit, a stationary hollow member extending through said unit and communicating with said reservoir, and a source of anti-freeze fluid connected to said member.

2. The combination with an impeller unit of 60 a means for preventing ice formation comprising a reservoir of anti-freeze fluid, a stationary conduit centrally located within said impeller unit, and fluid discharging means mounted on the front end of said impeller unit, said fluid discharging means communicating with said reservoir through said conduit.

3. In aircraft apparatus, a propeller mechanism, a streamlined member secured to said mechanism, a chamber being formed between said member and said mechanism, said member having openings therein connecting said chamber with the exterior of said member, means drivably connected to said mechanism, a reser-

voir of anti-freeze fluid, stationary communicating means extending through said first-named means and connecting said chamber to said reservoir, and valve means operatively associated with said connecting means.

4. In aircraft apparatus, a propeller mechanism, a streamlined member secured to said mechanism, a chamber being formed between said member and said mechanism, said member having openings therein connecting said chamber with the exterior of said member, means drivably connected to said mechanism to be driven thereby, means for interrupting an electric current mounted on said last-named means, a reservoir of anti-freeze fluid, means extending through said first-named means and connecting said reservoir and said chamber, and a valve mechanism interposed in said last-named means.

5. The combination with an impeller unit having a chamber therein communicating with the external surface thereof of deicing means adapted to prevent ice from forming on said surface, said deicing means comprising a reservoir of anti-freeze fluid, a conduit from said reservoir to the interior of said unit, a valve mechanism operatively connected to said conduit to control the fluid flow therethrough, and a stationary tube extending centrally through said unit and connecting said conduit with said chamber.

6. In a propeller unit having a propeller and a hub therefor, an anti-freeze fluid reservoir consisting of a stream-lined hub cap with a plurality of discharge openings therein and the front end of said hub, said discharge openings constituting the only passage from said reservoir to the exterior of said propeller unit, one of said openings being located in the leading end of said unit approximately coincident with the axis of said unit.

7. In aircraft apparatus, a propeller mechanism, a streamlined member secured to said mechanism, a chamber being formed between said member and said mechanism said member having openings therein connecting said chamber with the exterior of said member, means drivably connected to said mechanism, a reservoir of anti-freeze fluid, stationary communicating means extending through said first-named means and connecting said chamber to said reservoir.

8. The combination with an impeller unit having a chamber therein communicating with the external surface thereof of deicing means adapted to prevent ice from forming on said surface, said deicing means comprising a reservoir of anti-freeze fluid, a conduit from said reservoir to the interior of said unit, and a stationary tube extending centrally through said unit and connecting said conduit with said chamber.

9. In a propeller unit having a hub member, a hollow drive shaft and propeller blades secured to said hub member, a streamlined hub cap attached to the leading edge of said hub member to form a chamber between said cap and hub member, said hub cap being provided with discharge openings, a plurality of said openings being located adjacent the periphery of said cap and at least one opening being located substantially at the foremost point of said cap, a reservoir of anti-freeze fluid, a conduit from said reservoir, and a stationary capillary tube connecting said conduit with said chamber, said tube extending centrally through said drive shaft.
